COMBINED MEMO HOLDER AND PEN STAND

Chuzo Mori, Tokyo, Japan, assignor to Carl
Manufacturing Company Ltd., Tokyo, Japan

Filed June 4, 1973, Ser. No. 366,694

Claims priority, application Japan Mar. 17, 1973

Term of patent 14 years

Int. Cl. D19—02

U.S. Cl. D19—78

FIG. 1.

FIG. 4.

FIG. 2.

FIG. 3.

FIG. 5.

FIG. 6.

FIG. 1 is a front perspective view of a combined memo holder and pen stand embodying my new design;
 FIG. 2 is a bottom plan view thereof;
 FIG. 3 is a right side elevational view thereof;
 FIG. 4 is a rear elevational view thereof;
 FIG. 5 is a top plan view thereof;
 FIG. 6 is a left side elevational view thereof; and
 FIG. 7 is a front elevational view thereof.
 I claim:
 The ornamental design for a combined memo holder and pen stand, substantially as shown.
